UNITED STATES PATENT OFFICE.

WILLIAM W. JACKSON, OF PHILADELPHIA, PENNSYLVANIA, ASSIGNOR TO
MACKELLAR, SMITHS & JORDAN, OF SAME PLACE.

DESIGN FOR A FONT OF PRINTING-TYPE.

SPECIFICATION forming part of Design No. 13,586, dated February 6, 1883.

Application filed November 18, 1882. Term of patent 14 years.

To all whom it may concern:

Be it known that I, WILLIAM W. JACKSON, (assignor to MACKELLAR, SMITHS & JORDAN,) of the city and county of Philadelphia, Pennsylvania, have invented and produced a new and original Design for a Font of Printing-Type, of which the following is a specification.

The nature of my design is clearly shown in the accompanying typographic impression, to 10 which reference is made; and it consists of an ornamental text-letter the face of which is ornamented by a series of light lines following the configuration of the letter. The letters C G O Q are ornamented about centrally to the 15 right of the left-hand up and down portion by the rhomboidal shaded ornament, as shown, while the rest of the letters, except the letters S and X, are ornamented upon the left by the

flourishes, as shown. The letters B, C, D, E, G, J, L, M, O, U, V, W, and Z are further ornamented by a light vertical line extending from the upper to the lower portion of the letter.

In the lower-case and numerals the character of the design is preserved, save that the 25 flourishes, rhomboidal ornaments, and light vertical lines are omitted.

Having now described my invention, I claim as new—

The design for a font of printing-type, as 30 shown and described.

WM. W. JACKSON.

In presence of—

C. F. HUCH,
HERMAN METIUS.
